UNITED STATES PATENT OFFICE.

WILSON S. HAWKER, OF DAYTON, OHIO.

WOOD-TURNING MACHINE.

1,111,795.

Specification of Letters Patent. Patented Sept. 29, 1914.

Application filed May 5, 1910. Serial No. 559,631.

To all whom it may concern:

Be it known that I, WILSON S. HAWKER, a citizen of the United States, residing at Dayton, in the county of Montgomery and State of Ohio, have invented certain new and useful Improvements in Wood-Turning Machines, of which the following is a specification.

My invention relates to wood working machinery and particularly to a wood turning machine adapted to produce either straight round stock or round stock of varying diameters.

The object of the invention is to simplify the structure as well as the means and mode of operation of such machines whereby they will not only be cheapened in construction but will be more efficient in operation, substantially automatic, easily operated, and unlikely to get out of repair.

A further object is to provide a variable feed mechanism whereby the rate of feed may be varied.

A further object is to provide means for automatically adjusting the feeding device to compensate for variations in the rough stock to be operated upon and further, to automatically center the rough stock irrespective of its varied dimensions.

A further object is to provide means whereby the machine may operate upon short lengths of stock and whereby such short lengths may be supported at a point in proximity to the cutters.

With the above primary and sundry other incidental objects in view as will more fully appear in the specification, the invention consists of the features of construction, the parts and combinations thereof and their mode of operation, or their equivalents, as hereinafter described and set forth in the claims.

Figure 1 is a side elevation of the assembled machine. Fig. 2 is a front elevation viewed from the right in Fig. 1. Fig. 3 is a longitudinal vertical section through the machine. Fig. 4 is a transverse sectional view at right angles to that of Fig. 3 and viewed from the right. Fig. 5 is a top plan view of the assembled machine. Fig. 6 is a sectional plan view. Fig. 7 is a detail view partly in section of the means for regulating the tension of the feed rolls. Fig. 8 is a sectional view of the adjustable master cam for the variable turning mechanism. Fig. 9 is a detail view of the adjustable support

for the idler gear in the drive train of the variable turning mechanism. Fig. 10 is a side elevation of one of the swinging carriers of the feed rolls. Fig. 11 is a vertical section of the swinging carrier shown in Fig. 10. Fig. 12 is a perspective view of adjustable bushing for the feed roll spindle. Fig. 13 is a perspective view of the adjusting wedge of the feed roll spindle bushing. Fig. 14 is a plan view of the assembled machine equipped with a turning head for turning straight stock. Fig. 15 is a perspective view of the interchangeable square sleeve for the turning head.

Like parts are indicated by similar characters of reference throughout the several views.

General description.—The turning machine forming the subject matter hereof comprises a revoluble head carrying a plurality of adjustable cutters. The head is supported in bearings upon a main frame in the form of a casing or pedestal. The crude stock is introduced into the machine in the form of square sticks which are passed through the revoluble head and engaged by the cutters. At each side of the turning head the stock is engaged by revolving feed rolls. The feed rolls are positively driven and so mounted as to swing to and from each other to compensate for variations in the stock. By interengaging gear teeth upon the feed roll carriers the respective rolls are moved in unison thereby serving to center the stock irrespective of its diameter. Within the supporting casing or pedestal is contained means for reversing the feed rolls whereby the stock may be driven in either direction through the turning head. The cutter bits upon the turning head are adjustable and means including a master cam are provided for adjusting the cutter bits while in motion, thereby enabling the machine to produce work of varying diameter. As the turned work emerges from the cutter head it passes through the sanding attachment by which it is given a smooth or finished surface. In constructing the machine there is employed a main frame or pedestal 1 in the form of a rectangular casing provided with openings closed by doors 2 by which access may be had to the interior thereof. Supported on the top of the pedestal 1 is an elevated bearing 3 in which is journaled the sleeve 4 of the turning head.

Variable feed mechanism.—Secured to the

sleeve 4 of the turning head by screw threads or by other engaging means is a drive pulley 5 having formed integral therewith a friction disk 6 having a convex surface. 5 Mounted within the casing or pedestal 1 is a cross tree or bracket 7 in which are mounted stationary vertical shafts 8 extending upward to the top of the pedestal. Slidingly mounted on the vertical shafts 8 is 10 an adjustable head 9 carrying therein a horizontal countershaft 10 upon which is slidingly mounted a friction disk 11 spring pressed by a helical spring 12 into contact with the friction disk 6 of the drive pulley 5. The friction disk 6 rotating with the pulley 5, which is driven by a belt from the line shafting or other suitable source of power, drives the friction disk 11 in unison therewith. The friction disk 11 is provided 15 with a contact strip 13 of leather or other suitable material and the relative speed of the friction disks 11 and 6 depends upon their point of engagement. Mounted in suitable bearings in the pedestal 1 is a vertical 20 adjusting screw 14 engaging the sliding head 9 and carrying a bevel pinion 15 meshing with a similar pinion upon a horizontal countershaft 16 carrying at its extremity a crank handle 17 by which means the 25 adjustable head 9 may be raised and lowered on the guiding shafts 8, thereby varying the point of contact between the friction disks 11 and 6 to and from the periphery of the disk 6. When the adjustable head 30 9 is lowered whereby the point of contact between the friction disks will be adjacent to the periphery of the disk 6, the speed of the driven friction disk 11 will be accelerated and upon the raising of the adjustable head 35 9 by means of the adjusting screw 14 the point of contact between the friction disks will be adjacent to the center of the disk 6 and the speed of the driven disk 11 will be reduced. The transverse shaft 10 upon 40 which is carried the friction disk 11 also carries a bevel pinion 18, meshing with a corresponding bevel gear 19 journaled in the head 9 and engaging by a feather and groove connection a vertical revoluble shaft 45 20. The construction is such that as the head 9 is raised and lowered the bevel gear 19 will move therewith and will slide upon the vertical shaft 20 which it will continue to rotate. At its lower extremity the vertical shaft 20 carries a bevel pinion 21 which 50 meshes with two oppositely disposed bevel gears 22 provided with elongated sleeves or hubs 23 loosely journaled on the transverse shaft 24 provided with suitable bearings 25 26 in the main frame or pedestal. The inner or adjacent faces of the bevel gears 22 are provided with clutch teeth to be alternately engaged by corresponding teeth 27 on the sliding clutch member 28 mounted 30 on the transverse shaft 24 and engaged

therewith by a spline and groove connection. By shifting the clutch member 28 from engagement with the clutch teeth of one bevel gear 22 to engagement with those of the opposite gear 22 the direction of rotation of the transverse shaft 24 may be reversed and by moving the clutch member 28 to an intermediate position it will be disengaged with both the bevel gears 22 and the transverse shaft 24 will remain at rest. 70 The shaft 24 extends through the side of the pedestal 1 and carries a gear pinion 29 meshing with an idler gear pinion 30 loosely journaled on the shaft or stud 16 which idler gear in turn meshes with two gear pinions 31 mounted on the extremity of transverse shafts 32 located adjacent to the opposite sides of the pedestal 1. The transverse shafts 32 are provided with suitable journal boxes 33 secured upon the interior of the pedestal. Each of the transverse shafts 32 carries two bevel gears 34 which mesh with corresponding bevel gears 35 on the lower extremities of vertical shafts 36 located adjacent to each corner of the pedestal and provided with bearings in inward extensions 37 formed integral with the pedestal. The integral extensions 37 are provided with a central opening sufficiently large to accommodate the shaft 36 and an adjustable bushing 38. The bushing 38 extends into the central opening of the extension 37 and conforms to the shaft 36. Adjusting screws 39 in the sides of the pedestal 1 bear upon the bushing 38 and serve to adjust said 100 bushing to compensate for wear. The bushing 38 is provided with a vertical conduit 40 which forms an oil receiver from which suitable ducts lead to the bearing of the shaft 36. The relation of the bevel gears 34 on the transverse parallel shafts 32 with the corresponding pinions 35 upon the vertical shafts 36 are such that all of the four vertical shafts 36 will be rotated in unison in the same direction and with the 110 same speed. It will be readily seen that by shifting the clutch member 28 intermediate the bevel gears 22 from engagement with one of said gears to engagement with the opposite gear that the direction of rotation of the vertical shafts 36 will be reversed. In order to shift the clutch member 28 there is provided a ring or collar 41 inclosing the clutch member 28 and having opposite 115 extending arms 42 engaged with reciprocating bars 43 located at opposite sides of the pedestal and carried on rock arms 44 secured upon transverse shafts 45 journaled in the pedestal 1 at opposite sides thereof. Each of the rock shafts 45 projects in opposite directions beyond the pedestal and each carries a shifting lever 46. There will thus be a shifting lever located on each side of the machine for the convenience of the operator. It is obvious that one lever might 125 130

be dispensed with and the shifting of the mechanism to reverse the direction of the feed shafts accomplished from one side of the machine only.

- 5 *Compensating feed device.*—The vertical shafts 36 extend above the top of the pedestal 1 and have journaled thereon swinging feed roll carriers 47. The swinging carriers 47 are shown in detail in Figs. 10 and 11 70 and are journaled on the upper extremities of the shafts 36. The lower portion of the swinging carriers is recessed to form a gear casing 48. Within the gear casing 48 and secured upon the shaft 36 is a gear pinion 49 meshing with a corresponding gear pinion 50 on the revoluble stud 51 journaled in the swinging carrier 47. The stud 51 carries at its upper extremity the feed roll 52 which is secured to and rotates therewith. 75
- 10 The construction is such that the rotation of the vertical shaft 36 drives the stud 51 and feed roll 52 in unison therewith by means of the gears 49 and 50 and the swinging carrier may be oscillated about its 80 journal connection upon the shaft 36 without interfering with the rotation of the feed roll. In order to provide for the adjustment of the feed rolls by the oscillation of the swinging carrier about the shaft 36 and 85 90 95
- 15 in order to insure the movement of the corresponding feed rolls in unison there is provided on each of the swinging carriers a gear segment 53 concentric with the pivotal connection of the carrier upon the shaft 36. 100
- 20 The gear segments 53 of each pair of swinging carriers intermeshing with the gear segment of the corresponding swinging carrier as shown in Figs. 5, 7 and 14. The swinging movement of the swinging carriers about their pivotal connection upon the shaft 36 moves the respective feed rolls to and from the center line or the axis of the work when passing through the machine. The interengagement of the gear segments 105 110
- 25 causes the swinging carriers to move equally whereby the feed rolls are equidistant from the center line thereby serving to center the work which is engaged between the rolls. The feed rolls will yield equally to compensate for any variation in the diameter of the work. Supported on a suitable bracket attached to the pedestal 1 is a cylindrical housing 54 within which is located a worm 55 engaging the teeth of one 115 120 125
- 30 of the gear segments 53 of one of the swinging carriers. The worm 55 may be rotated by a hand wheel 56 secured upon the stem 57 thereof. In addition to its revoluble movement the worm 55 is capable of a reciprocatory movement within the cylindrical housing 54 against the tension of a helical spring 58 coiled about the stem 57 and between the collar 58^a upon the worm 55 and the head of the cylindrical housing 54. 130
- 35 The tension of the spring 58 is such that will tend to keep the swinging carriers and feed rolls in their closed position. However, upon the feed rolls engaging an enlargement in the work or stock the carriers will yield to permit the passage of such large portion against the tension of the spring 58 the worm 55 reciprocating within the housing 54 and compressing the said spring 58. After such enlarged portion of the work or stock has passed the feed rolls 75 80 85 90 95 100 105 110 115 120 125 130
- 40 the spring 58 will return the swinging carriers and feed rolls to normal position and will maintain the carriers and feed rolls in condition to impinge the stock or work. The action of the feed rolls in thus swinging to and from the turning head facilitates the clearing of the head of defective stock and gives the required tension upon the feed rolls while at the same time centering the stock as it enters the turning head and the finished work as it leaves said head. There are two sets of swinging carriers and feed rolls with their adjusting worm and tension spring one set located at each side of the turning head. The set of feed rolls at the intake side of the head are provided with a substantially V-shaped groove to conform to the square surface of the crude stock while the set of feed rolls at the offtake side of the turning head are provided with a semicircular groove to conform to the finished work. Inasmuch as there will be considerable wear upon the stud 51 carrying the feed rolls means are provided for compensating for such wear comprising a split bushing 59 upon the stud, one-half of which bushing is provided with an annular wing 60. A similar split bushing 61 is provided for the journal bearing of the swinging carrier upon the upper extremity of the shaft 36. The annular wings 60 of the respective split bushings 59 and 61 extend toward each other and the swinging carrier is provided with an opening for the insertion of a key 62 intermediate the bearing of the shaft 36 and the stud 51. The key 62 is provided with an inclined groove 63 on each side thereof which inclined grooves are adapted to engage the annular wings 60 of the respective split bushings 59 and 61 and forces 115 120 125
- 45 said bushings carrying said annular wings into close contact with the stud 51 and shaft 36. The key 62 might be made of sufficient length to extend somewhat above the swinging carrier and be driven down in order to tighten the respective bearings. However, in such construction the jarrings incident to the use of the machine might cause the key to unnecessarily tighten the bearings resulting in the injury thereof. To obviate this 130
- 50 the construction is such that the key will pass to a limited distance into the swinging carrier and between the annular wings of the respective bearings. In order to compensate for wear of the bearings the key 62 130

is removed and a strip of packing or paper is laid in the tapered groove 63 and the key is returned to place, the packing within the groove serving to tighten the respective bearings by forcing the annular wings 60 in opposite directions.

Supporting devices.—Projecting from the cylindrical housing 54 within which is contained the adjusting worm is a lug 64 having therein an undercut or gibbed slot 65 which slot is adapted to be engaged by several attachments for work of different character. For handling straight rods, the crude stock for which is sawed substantially straight and even throughout, supporting wheels or rollers 66 may be engaged with the slotted lug 64, the journal of the wheel or roller 66 being provided with the head adapted to engage in the gibbed slot 65 where it is secured by a hand wheel 67. The supporting wheel or roller may be adjusted vertically within the limits of the gibbed slot 65 according to the diameter of the work being produced. For operating upon work of varying diameter or upon crude stock that varies greatly in size owing to fault of sawing, a compensating support may be attached to the lug 64 as shown in Fig. 1. This compensating support comprises an inclined member 68 stationarily secured upon the lug 64 by means of a bolt engaging in the gibbed slot 65 upon which there is adapted to ride a sliding inclined block 69. The stationary block 68 and the sliding block 69 are preferably interengaged by a tongue and groove or gibbed connection. The upper surface of the sliding block 69 is provided with a longitudinal groove 70 shown in Fig. 5 within which the work will ride. A link 71 connects the sliding inclined block 69 with the swinging carrier 47. While the feed rolls are adapted to center the work horizontally the sliding block or support 69 will center the work vertically. When the swinging carriers are forced outward to permit the passage of an enlargement of the work or stock due to the engagement of such enlarged portion with the feed rolls, the movement of the carriers will be transmitted through the link 71 to the sliding inclined block 69 which will be pushed down the incline of the stationary block 68 to compensate in a vertical plane for such enlargement of the work or stock. Thus the work will not only be centered in a horizontal plane but also in a vertical plane and the supporting block 69 will be raised and lowered by shifting it up and down the incline to compensate for each variation of the material passing between the feed rolls. The compensating support comprises the inclined blocks 68 and 69 and is interchangeable with the revoluble supporting wheel 66. For using stock which varies greatly through irregular or faulty sawing it is de-

sirable to employ the compensating support comprising inclined blocks 68 and 69 upon the intake side of the machine while the revoluble roller or wheel may be employed upon the discharge side of the machine when the work produced is of substantially equal diameter throughout. However, when work of variable diameter is being produced the compensating support is preferably used upon the discharge side of the machine while if the stock therefor is very regularly and evenly sawed the roller 66 may be movable upon the intake side. There is also employed with the machine a sanding attachment for giving a finished surface to the work which is adapted to be supported upon the lugs 64 being interchanged with the supporting devices before described. The turning head employed with the machine may be either of a type suitable for turning straight stock in which the cutters are secured in fixed positions or the head may be made of a type suitable for work of variable diameter in which the adjustment of the cutters is varied during the operation of the machine to produce work of pre-determined form.

The turning head secured to or formed integral with the sleeve 4 and adapted to be driven by the pulley 5 comprises a circular member 72 from the face of which projects a plurality of lugs 73 flush with the periphery of the circular member 72. Eccentrically pivoted upon the circular plate 72 are a plurality of cutter supports 74 having extensions 75 normally resting upon the lugs 73. In each of the cutter supports 74 is an opening through which projects a stud 77 carrying a retaining nut by which the cutter supports are retained in position. The cutter supports are capable of an oscillation about their eccentric pivotal connection 78. This turning head construction is fully described in my prior Patent No. 949,765.

Cutter bits.—The cutter bits 90 are adjustably secured upon the supporting members 74 by clamping nuts 91. The cutter bits 90 comprise a member flat throughout the greater portion of its extent but upturned or curved at its forward edge; that is, the edge first engaging the work. Each cutter is provided with a slot 92 through which projects the stud of the clamping nut 91 whereby the bit is adjustable longitudinally upon the supporting member 74 to compensate for wear. The cutting edge of the bit is somewhat L-shaped, being substantially straight throughout the greater portion of its extent and provided with a portion 93 extending somewhat beyond the main portion of the cutting edge and bearing upon the work. The portion 93 of the bit projects tangentially to the finished work; the four cutters supporting the work at diametrically opposite points. The portion 93 thereby forms a variable throat within which the

work is supported and by which the work is centered. This variable throat being formed by the extensions 93 integral with the cutter bits varies in unison therewith and having but four points of contact with the work, there will be but little friction or torsional strain. The under side of the portion 93 of the bit is ground off slightly to provide clearance. This clearance is so slight as to be hardly perceptible yet it is quite important and in practice has been found to be almost equivalent to the difference between success and failure. By means of the extensions 93 forming a rectangular orifice or throat for a support of the work which is variable with the adjustment of the cutters, the work is at all times supported at a point adjacent to the point of operation of the cutters and regardless of the varying diameter of the finished work. For operating on certain grades of stock and producing certain results it is desirable that the cutter bits be reversed. The crude stock is adapted to be passed through the turning head before being engaged by the cutter bits. However, it is sometimes desirable to reverse the operation and pass the crude stock through the forward side of the turning head, the finished work passing through the head in which case the cutter bits may be reversed upon their pivotal supports thereby bringing the supporting extension 93 of the bit adjacent to the face of the turning head and the curved edge or working side of the bit at the side removed from the turning head. Such changes involve merely the transposing of the cutter bits. It is thought that it will be obvious without the necessity of separate illustrations. The clearance on the backs of the four opposing cutters causes the necessary freedom for the rotation of the head and cutters about the turned stock while at the same time supporting it. This clearance in the rectangular orifice or supporting throat corresponds in principle with the clearance obtained in the ordinary solid turning head or chuck in common use by setting the cutting edge of the cutter inward toward the center to turn the stock a trifle smaller than the bore of the chuck as is the usual custom.

Supporting means for small or short stock.—When turning work of very small diameter the crude stock is liable to be twisted or broken by the torsional strain unless supported to a point adjacent to the working point of the cutter bits. In order to provide for such support for the stock there are provided interchangeable mandrels 111 shown in detail in Fig. 27, having rectangular openings 112 centrally therein of a size approximately equal to the size of the crude stock to be operated upon. The mandrel 111 is secured by being clamped in a support 113 mounted on the top of the pedestal. The

support 113 also forms an inclosed housing for the driven friction disk 11. The mandrel 111 is secured therein by a yoke 114 engaged by nuts 115. The mandrel 111 projects through the sleeve 4 of the turning head to a point adjacent to the cutters as shown in Fig. 3. The mandrel 111 is held stationary while the turning head revolves about it. The crude or squared stock is passed through the mandrel 111 to the cutters and the mandrel supports the stock and prevents it rotating with the cutters thereby preventing the stock from twisting and breaking, due to the torsional strain of the cutters operating thereon. The interchangeable mandrels are all of equal external diameter whereby they will fit the interior of the sleeve 4 of the cutter head and the mandrel support 113 but different mandrels may have central squared openings of different sizes to accommodate different sizes of stock. It is also desirable under some circumstances, to employ the mandrel for supporting the finished work when the cutters are used in reversed position as before mentioned in which case the mandrel becomes a support supplemental to the extensions 93 of the cutter bits.

While the turning mechanism hereinbefore described is especially adapted to turning work of variable diameters it is obvious that a turning head having stationary cutters thereon for turning rods of equal diameter throughout may be substituted for the variable turning mechanism. Such a turning head is shown in Fig. 14 in which the head comprises a flat plate or base 129 upon which are stationarily secured the cutter supports 130 carrying cutter bits 131 which are identical with the cutter supports 73 and the cutter bits 90 except that such parts are stationarily secured upon the base plate 129. The cutter supports and cutter bits may be adjustable thereon but are not variable while the machine is operating but are adjusted to a given size of rod in which adjustment they are secured. Such a head may be used interchangeably with the variable shape turning mechanism without interfering with the remainder of the machine.

Having thus described my invention I claim:

1. In a turning machine, intermeshing gear sectors, feed rolls eccentrically carried by the sectors whereby an oscillation of the sectors will cause the rolls to move to and from each other, means for manually adjusting the sectors to adjust the feed rolls to predetermined normal relation one with the other, and yielding means tending to maintain the sectors in their predetermined adjusted positions against the tension of which the sectors may move from such predetermined adjusted positions and adapted to return the sectors to such predetermined ad-

- justed positions after each movement therefrom, substantially as specified.
2. In a turning machine, a turning head, a plurality of feed rolls, adapted to rotate at uniform rates of speed, variable driving connections between the turning head and the rolls comprising two friction disks rotating in parallel planes with their adjacent faces in contact one with the other, a sliding head upon which one of the friction disks is carried, driving connections carried by said sliding head adapted to maintain operative connection with the feed rolls throughout all positions of adjustment, the sliding movement of said head being adapted to cause the disks to engage one with the other at different distances from the center of rotation thereby varying the relative rate of rotation of the turning head and feed rolls.
3. In a turning machine, a main frame, a turning head and a drive pulley mounted thereon, a friction disk revoluble with the pulley, guides within said frame, a movable head slidably mounted on said guides, a driven friction disk carried by said head, a counter shaft carried in said head, a bevel pinion carried by said shaft and a second pinion carried by said head with which the first pinion meshes, a revoluble shaft journaled in the main frame driven by the second mentioned and on which the pinion is longitudinally movable upon adjustment of the sliding head, a plurality of feed rolls, driving connections between the revoluble shaft and feed rolls, the speed of such rolls being varied by the adjustment of the sliding head.
4. In a turning machine, a main frame, a turning head and a drive pulley mounted thereon, a friction disk revoluble with the pulley, guides within said frame, a movable head slidably mounted on said guides, a driven friction disk carried by said head, means for shifting said head and thereby varying the engaging point of the friction disks, a transverse drive shaft, two oppositely disposed gears loosely journaled on said shaft, an intermediate driving pinion meshing with both said gears, driving connections between the driven friction disk and said driving pinion, a shiftable clutch adapted to engage either of the gears with the drive shaft, whereby the direction of rotation of the shaft may be reversed by alternately engaging the said gears therewith, a plurality of revoluble feed rolls and driving connections between the feed rolls and drive shaft.
5. In a turning machine, a main frame, a turning head and a drive pulley mounted thereon, a friction disk revoluble with the pulley, guides within said frame, a movable head slidably mounted on said guides, a driven friction disk carried by said head, the point of engagement of the friction disks

and thereby the relative speed of the disks being varied by the adjustment of the sliding head, a drive shaft, reversible driving connections between the driven friction disk and drive shaft and a plurality of feed rolls 70 driven by said drive shaft.

6. In a turning machine, a main frame, a turning head and a drive pulley mounted thereon, a plurality of revoluble feed rolls, drive mechanism therefor between the drive pulley and feed rolls, including two relatively adjustable friction disks and reversible driving gears whereby the rolls may be driven in either direction at variable rates of speed.

7. In a turning machine, a main frame, a turning head and a drive pulley mounted thereon, a plurality of revoluble feed rolls, drive mechanism therefor between the drive pulley and feed rolls, including a movable clutch member whereby the direction of rotation of the feed rolls may be reversed, parallel rock shafts mounted in the frame, rock arms on said shafts, reciprocating bars actuated by the rock arms and in turn actuating the movable clutch member, operating levers on each of the rock shafts and at opposite sides of the machine whereby the rotation of the feed rolls may be reversed from either side of the machine by the operation of either lever.

8. In a turning machine, a plurality of feed rolls, swinging carriers in which the rolls are journaled, intermeshing gear segments on corresponding swinging carriers 100 whereby the carriers will swing in unison, and an adjusting worm engaging the segment of one of the carriers and by its rotation adapted to positively adjust the feed rolls to and from each other.

9. In a turning machine, a plurality of feed rolls, swinging carriers in which the rolls are journaled, intermeshing gear segments on corresponding swinging carriers whereby the carriers will swing in unison, 110 a reciprocatory adjusting worm engaging a segment of one of said carriers, a spring against the tension of which the worm is adapted to reciprocate, whereby the rolls may automatically adjust themselves to irregularities in the work passing between them.

10. In a turning machine, a main frame, a turning head, a plurality of feed rolls arranged in pairs, swinging carriers in which the rolls are journaled, revoluble drive shafts on which the swinging carriers are journaled, gears carried on said shafts, intermeshing gear pinions carried on the roll trunnions and meshing with the first mentioned gears, intermeshing gear segments carried by the corresponding swinging carriers, means tending to hold the rolls in engagement with the work but permitting the rolls to yield for irregularities in the work 130

passing between the rolls, and means for positively adjusting the position of the rolls in relation to the axis of the work independent of their movement due to irregularities 5 of the work.

11. In a turning machine, a main frame, a turning head, a plurality of feed rolls, swinging carriers in which the rolls are journaled, intermeshing gear segments on the 10 carriers whereby the carriers will move in unison, a reciprocating support for the work, an inclined surface on which the support rides, a link connecting the support and swinging carriers whereby when the carriers

swing outward, the reciprocating support 15 will move down the inclined surface and away from the axial line of the head, and when the rolls approach each other the support will move up the incline and approach the axial line of the head in unison with the 20 rolls.

In testimony whereof, I have hereunto set my hand this 26th day of April, A. D. 1910.

WILSON S. HAWKER.
